executors, assignors to The Gray Processes Cor-
poration, Newark, N. J., a corporation of Dela-
ware

Continuation of application Serial No. 453,637,
May 19, 1930. This application July 24, 1934,
Serial No. 736,676

3 Claims. (Cl. 196—10)

This application is a continuation of the co-
pending application Serial No. 453,637, filed May
19, 1930, which is a continuation-in-part of the
application Serial No. 664,893, filed September
26, 1923, patented May 20, 1930 as Patent No.
1,759,812.

This invention relates to the refining of fixed
gases occurring naturally in petroleum or re-
sulting from the processing of petroleum in the
refinery and has for an object the recovery from
such fixed gases of hydrocarbons lying in the
gasoline boiling range.

It is quite old in the art to recover gasoline
as a liquid from natural gas or from fixed gas
resulting from the distillation or cracking of
petroleum. However, in previous methods, there
has been accomplished merely the removal of
hydrocarbons which, under ordinary conditions
and by themselves are liquid, but are carried by
a great amount of fixed gas. These compounds
are now removed from fixed gases by several
methods or combinations of methods, but the
usual method is compression followed by solu-
tion in a liquid. In all these methods, only nor-
mally liquid hydrocarbons carried in the fixed
gas are removed and there is no alteration of
chemical constitution of any part of the fixed gas.

According to the present invention, certain
unstable, unsaturated compounds which may be
30 of the diolefins or related types contained in the
fixed gas are polymerized by the action of a solid
adsorptive material to other compounds of totally
different physical and chemical properties.
These new compounds lie within the gasoline
35 boiling range and are liquid at ordinary condi-
tions of temperature and pressure and thus dif-
fer from the fixed gases from which they were
formed. Fixed gases of the character above re-
ferred to may be contacted with solid adsorptive
40 material separately or may be contacted simul-
taneously with cracked gasoline vapors, in the
manufacture of which by cracking the fixed
gases are produced and which contain unstable,
unsaturated compounds which tend to discolor
45 on exposure to light and to form deposits, there-
by increasing the yield of gasoline from such va-
pors. Also, the method may be used to increase
the yield in cracking processes of the type which
produce gasoline of such color and stability that
50 it does not need to be subjected to decolorization
treatment.

The accompanying drawing discloses one form
of apparatus which may be used for practicing
the invention.

55 This apparatus consists of a treating tower 10

preferably equipped with a layer 11 of heat in-
sulating material. Within the tower there is
provided a conical fluid permeable shelf 12 ter-
minating in a discharge spout 13 controlled by
a valve 14. On the shelf 12 is supported a charge
15 of solid adsorptive material, the shelf 12 be-
ing impervious to such material. A manhole 16
closed by a cover 17 is provided for introducing
the solid adsorptive material into the treating
tower. A vapor inlet pipe 18 controlled by a
10 valve 19 communicates with the upper part of
the tower and a vapor outlet pipe 20 controlled
by a valve 21 leads from the treating tower at
a point below the shelf 12. A trapped drainage
15 pipe 22 controlled by valve 23 leads from the
bottom of the tower.

Fixed gases or fixed gases combined with
cracked hydrocarbon vapors are introduced into
the treating tower 10 through the pipe 18 and
are caused to pass through the solid adsorptive
material 15 and are then conducted by the pipe
20 to a condenser (not shown). During the pas-
sage of the fixed gases through the solid ad-
sorptive material, certain reactive unstable, un-
saturated constituents are polymerized into com-
pounds lying in the gasoline boiling range. The
cracked vapors are refined by the solid adsor-
ptive material as described in the Patent No.
1,340,889 and application, Serial No. 664,893. A
suitable solid adsorptive material is fuller's
30 earth, but other adsorptive material having simi-
lar selective polymerizing characteristics may be
used. The polymerization of the unstable, un-
saturated hydrocarbons in the fixed gases re-
sults in an increased yield of gasoline in a re-
fining process wherein cracked hydrocarbons
35 mixed with fixed gases produced in the cracking
operation are refined by being passed through
a bed of solid adsorptive material.

The fixed gases, after passage through the
40 treating material, may still carry some poly-
merized gasoline which is not liquefied due to the
vapor pressure of the remaining gases. This
gasoline may be recovered from the gases by any
of the well-known "compression" or "adsorp-
45 tion" processes.

Although the process has been described by
reference to fixed gas from cracking processes
having as their object the production of gasoline,
it may also be practiced in connection with the
cracking of oil to gas. In such cases, the cracked
gas, such as is intended for use in enriching water
gas and the like, is treated in the manner shown.
Unstable, unsaturated compounds in the gas are
polymerized to liquids in the gasoline boiling
55

range, while the remainder of the gas is purified by passing through or contact with the solid adsorptive material.

The process is also able to stabilize a cracked gasoline to some extent by converting normally low boiling unstable, unsaturated hydrocarbons having a high vapor pressure to higher boiling liquid which, while still within the boiling range of gasoline have a much lower vapor pressure 10 than the low boiling unsaturated hydrocarbons.

The process may be carried on either under atmospheric or super-atmospheric pressure and the vapors and fixed gases to be treated may be supplied directly from a cracking unit or from a 15 re-run still. The process is not limited to any particular state of conditions and the invention is limited only by the scope of the appended claims. When treating fixed gas mixed with gasoline vapors, the temperature and pressure are 20 preferably those best suited to the treatment of the latter and are usually at or near the equilibrium boiling point of the mixture and at a pressure between atmospheric and 500 pounds per square inch or more. When treating fixed gas 25 separately, the temperature and pressure may be varied over a wide range, depending on the nature of the unsaturated compounds present and the amount of polymerization desired. With highly reactive unsaturated compounds atmospheric 30 pressure and normal temperature will bring about conversion. For less reactive unsaturated compounds higher pressures, even as high as 100 atmospheres and higher and temperatures of the order of 650° F. and above, will frequently be 35 found advisable.

What is claimed is:—

1. The process of obtaining valuable low-boiling normally liquid hydrocarbons suitable for use as motor fuel from hydrocarbon gases containing 40 gaseous unsaturated hydrocarbons, which comprises continuously passing a stream of said gases in the absence of added oxygen in contact with solid adsorbent catalytic material at an ele-

vated temperature and pressure for a sufficient period of time to effect a polymerization of said gaseous unsaturated hydrocarbons to normally liquid products, removing the treated stream of gases and products from the catalytic material and recovering said normally liquid products from the remaining unconverted hydrocarbon gases. 5

2. The process of obtaining valuable low-boiling normally liquid hydrocarbons suitable for use as motor fuel from hydrocarbon gases containing 10 gaseous unsaturated hydrocarbons resulting from the pyrolysis of hydrocarbon oils, which comprises continuously passing a stream of said gases in the absence of added oxygen through a bed of fuller's earth at an elevated temperature and 15 pressure for a sufficient period of time to effect a polymerization of said gaseous unsaturated hydrocarbons to normally liquid products, removing the treated stream of gases and products from the bed of fuller's earth and recovering said normally liquid products from the remaining unconverted hydrocarbon gases. 20

3. The process of obtaining valuable low-boiling normally liquid hydrocarbons suitable for use 25 as motor fuel from hydrocarbon gases containing gaseous unsaturated hydrocarbons, which comprises continuously passing a stream of said gases in contact with solid adsorbent catalytic material at an elevated temperature and pressure for a 30 sufficient period of time to effect a polymerization of said gaseous unsaturated hydrocarbons to normally liquid products, removing the treated stream of gases and products from the catalytic material and recovering said normally liquid products from the remaining unconverted hydrocarbon gases. 35
